[57] CLAIM

The ornamental design for a multiple receptacle electrical connector, as shown and described.

DESCRIPTION

FIG. 1 is a top, front and right side perspective view of a multiple receptacle electrical connector showing our new design;

FIG. 2 is a top plan view thereof;

FIG. 3 is a front elevational view thereof;

FIG. 4 is a left side elevational view thereof;

FIG. 5 is a bottom plan view thereof;

FIG. 6 is a rear elevational view thereof;

FIG. 7 is a cross-sectional view thereof taken along the line 7—7 of FIG. 3;

FIG. 8 is a cross-sectional view thereof taken along the line 8—8 of FIG. 3;

FIG. 9 is a top, front and right side perspective view of a first alternative embodiment of an electrical connector receptacle showing our new design;

FIG. 10 is a top plan view thereof;

FIG. 11 is a front elevational view thereof;

FIG. 12 is a left side elevational view thereof;

FIG. 13 is a bottom plan view thereof;

FIG. 14 is a rear elevational view thereof;

FIG. 15 is a cross-sectional view thereof taken along the line 15—15 of FIG. 11;

FIG. 16 is a cross-sectional view thereof taken along the line 16—16 of FIG. 11;

FIG. 17 is a top, front and right side perspective view of a second alternative embodiment of an electrical connector receptacle showing our new design;

FIG. 18 is a top plan view thereof;

FIG. 19 is a front elevational view thereof;

FIG. 20 is a left side elevational view thereof;

FIG. 21 is a bottom plan view thereof;

FIG. 22 is a rear elevational view thereof;

FIG. 23 is a cross-sectional view thereof taken along the line 23—23 of FIG. 19;

FIG. 24 is a cross-sectional view thereof taken along the line 24—24 of FIG. 19.
